AUDION AMPLIFIER

Paul O. Farnham and Raymond Asserson, Boonton, N. J., assignors, by mesne assignments, to Radio Corporation of America, New York, N. Y., a corporation of Delaware

Application October 3, 1929, Serial No. 397,123

13 Claims. (Cl. 179—171)

This invention relates to audion amplifiers and particularly to methods of and apparatus for avoiding distortion when audion amplifiers are so operated as to effect amplification of a relatively low order of magnitude.

The problem of volume control in radio frequency amplifiers is usually complicated by the introduction of unwanted effects, such as, for example, a decrease in selectivity as the sensitivity is decreased; detuning of one or more stages of the amplifier, and the introduction of distortion in the modulation of the impressed carrier. In cascaded amplifiers in which the volume control is based upon an adjustment of the control grid bias, or the screen-grid voltage in the case of tetrodes, distortion in modulation occurs when the sensitivity is reduced, for strong signals of the order of 0.2 volt or larger, to maintain a constant output. To keep the impressed signal strength below the point at which appreciable distortion arises, it has been the practice to reduce the signal voltage derived from the antenna by some form of manual control, such as a potentiometer.

Objects of the present invention are to provide a method of and an audion stage for amplifying carrier wave signals, the method and apparatus being characterized by an absence of distortion in modulation when the amplification is reduced to a low value.

A further object is to provide an amplifier stage capable of operating as a substantially linear amplifier when signal energy of the order of several volts is impressed upon the stage and the sensitivity of the stage has been reduced to a low value.

More particularly, an object is to provide an amplifier stage including a pair of audions connected in parallel across the stage input circuit, the amplified output from the audions being combined in phase opposing relation, whereby the stage amplification is determined by the difference between the amplification rates of the two audions.

These and other objects of the invention will be apparent from the following specification, when taken with the accompanying drawings, in which

Fig. 1 is an electrical diagram of one circuit embodying the invention;

Fig. 2 is a static characteristic of one audion, the curve showing plate current as a function of control grid bias;

Fig. 3 is a series of similar static characteristic

curves for the separate audions and for the amplifier stage of Fig. 1;

Fig. 4 comprises experimental curves showing the relationship between stage gain and differences in control grid biases for the stage shown in Fig. 1;

Fig. 5 comprises a similar curve showing the relationship between stage gain and differences in screen grid voltage in an amplifier of the type shown in Fig. 6;

Fig. 6 is a circuit diagram of an amplifier stage in which volume control is effected by adjustment of screen-grid voltages; and

Fig. 7 is a circuit diagram of another embodiment of the invention.

In the drawings, the reference numerals 1 and 2 indicate the two audions which, with the associated impedance network, form an amplifier stage in which the signal energy is impressed upon the two audions in parallel, but the amplified outputs from the tubes are combined in push-pull, or phase opposing relationship.

As shown in the drawings, the input circuit for the stage comprises an inductance 3, coupled to an inductance 4 in the antenna circuit, and shunted by a variable condenser 5 for tuning over a band of frequencies. The control grids G_1 of both audions are connected to the high potential terminal of the tuned circuit 3, 5 and the low potential terminal is grounded in the usual manner to the chassis or casing of the amplifier. The output circuit of the stage is provided by an inductance 6, shunted by a tuning condenser 7, the inductance being coupled to the inductances 8', 8'', in the anode circuits of audions 1 and 2, respectively. The anode inductances may, and preferably do take the form of a continuous coil, the anodes of the audions being connected to the opposite terminals of the coil, and the connection from the battery 9 being made to a central tap on the coil.

With this arrangement, the alternating currents flowing in inductances 8', 8'', induce currents of opposite phase in the stage output inductance 6 and the net output of the stage is determined by the difference in the current flow in the two anode inductances.

The positive potential for the screen grids G_2 may be obtained from the battery 9, preferably by means of an adjustable tap 10, and the usual by-pass condensers 11 are provided for the battery leads and between the cathodes and ground.

Control of amplification is effected by regulating the control grid biases impressed upon audions 1 and 2. Individual grid bias batteries 12', 12

12" are connected to the low potential or grounded side of the tuned input circuit and are shunted by potentiometers 13', 13", the adjustable contact arms 14', 14" of the potentiometers being connected to the cathodes of audions 1, 2, respectively. While not essential, the contact arms are preferably operated by a single insulated knob or dial 15, the arrangement being such that the bias voltages are changed in opposite sense upon movement of the contact arms.

The method employed will be apparent from a consideration of the curves of Figs. 2 and 3. The static characteristic curve A shows the relationship between control grid bias E_c and plate current I_p for a particular tetrode of the commercial type known as UY224, when operated with 75 volts on the screen-grid and 180 volts on the plate. The actual dynamic curve for a tetrode of high plate impedance is not identical with the static characteristic but is a curve of the same general nature and the static characteristic may therefore be employed to illustrate the principles involved. As indicated by the two sets of curves representing input signal voltage E_s and corresponding plate current I_p , Fig. 2, amplification is proportional to the slope of the characteristic and may be controlled by regulating the grid bias to place the operating point at any desired point on the characteristic. This general method of control is well known as has been previously employed to effect control of volume.

While the wave shape of I_p corresponding to operation at -2 volts grid bias is symmetrical about the quiescent point, the wave shape for I_p corresponding to low amplification at -4.5 volts grid bias is not symmetrical and indicates distortion in the modulation.

In the circuit of Fig. 1, the effective output is not determined by the amplification of either tube, but by the difference in their amplification rates since the amplified signal energy is combined in phase opposing relation. The magnitudes of the alternating current voltages in the respective plate circuits depend upon the position of the operating point on the characteristic curve of each tube, and this position is determined by the control grid bias of the respective tubes.

The effective amplification is therefore determined by the difference in slopes of the characteristic curves at the respective operating points. The net plate current curve for the stage may be determined graphically in the manner indicated in Fig. 3. Solid line curves A, B are the static characteristics for audions 1 and 2, respectively; the curves B₁, B₂, etc. being duplicates of curve B, but displaced therefrom by distances corresponding to 1 volt, 2 volts, etc., respectively, on the scale of abscissa. Net plate current curves C₂, C₁, etc., may be plotted to show the relationship between the effective plate current of the stage and grid bias when the volume control is so adjusted that the bias voltage on audion 2 is more negative than that on audion 1 by values of 2 volts, 1 volt, etc., respectively.

A mathematical analysis will show that, in general, the difference curves are of an order one power lower than the characteristic curves. The difference or net plate curves indicate that distortion in modulation may be substantially eliminated even when strong signals are received, by locating the operating points of the audions in regions on the respective curves which correspond to linear response regions on the net plate current curve, the stage gain being reduced to a

low value by making the bias on one tube but slightly different from that on the other tube.

The stage gain may be regulated by placing a fixed bias on one tube and adjusting the bias on the second tube, or the bias voltages may be simultaneously adjusted. When both voltages are adjusted, we prefer to keep the sum of the biases constant as their respective values are varied.

The curves of Fig. 4 represent the relation between stage gain and bias voltage differences for the amplifier circuit shown in Fig. 1, when employing UY224 tubes with screen-grid and plate potentials of 75 and 180 volts respectively. Curves D and E were obtained when the bias voltages on audion 1 were constant and equal, respectively to -1.5 and -6 volts. The data for curve F was obtained when the sum of the bias voltages E_c' and E_c'' on the tubes was maintained constant at -10 volts, while the individual biases were adjusted.

If the operating characteristics of the respective tubes and their associated networks were identical, the stage gain in each instance would fall to zero when the tube biases were equal. The fact that the gain curves do not fall to zero at point of zero difference in grid bias indicates that the operating characteristics of the two tubes were not identical.

The invention is equally applicable to volume control systems in which the emission, or the plate or screen grid potentials are varied to control the amplification.

For example, the circuit of Fig. 1 may be modified to permit the application of different screen-grid voltages to the respective audions.

An amplifier stage of this type is illustrated in Fig. 6, in which the separate bias batteries 12', 12" are replaced by a common bias battery 12, and individual leads and adjustable taps 10', 10", respectively, are provided for applying positive potentials to the screen-grids of audions 1 and 2.

The curve G of Fig. 5 shows the variation of stage gain as the screen-grid voltage of one tetrode was varied, the screen-grid voltage on the other tetrode remaining fixed at 75 volts, and the bias and plate voltages on both tetrodes being -1.5 and 180 volts, respectively. The operating range for volume control will, of course, include but one branch of the curve G, and for the particular tubes and circuit from which the plotted data was obtained, the control range corresponds to variation of the second screen-grid potential between zero and 53 volts.

It is not essential that the signal energy be impressed across the pair of audions in parallel since the same combination of amplified energy in phase opposing relation may be effected when the potentials on the control grids are of opposite phase and both audions feed the stage output circuit in parallel.

As shown in Fig. 7, an amplifier stage employing this method may include an input transformer having a primary 4 across which the signal voltage E_s is developed, and a secondary 3', the opposite ends of the secondary being connected to the respective control grids G₁ and the center point of the secondary being grounded. The plate circuits of audions 1, 2 have a common impedance 8 for transferring amplified energy to the stage output circuit 6, 7. The remaining circuit elements of the stage may be of appropriate arrangement and magnitude for effecting control of the amplification of one or both audions.

and, as shown in Fig. 7 these elements have the arrangement and are identified by the same reference numerals as corresponding circuit elements of the Fig. 1 circuit.

5 It will be apparent that the invention is not restricted to circuits employing tetrodes, or to the particular values mentioned in the above description of certain embodiments of this invention. While particularly useful as the first stage 10 of a cascaded amplifier, circuits embodying the invention may be used in subsequent stages, or in a plurality of the stages of an amplifier.

When employed for the amplification of unmodulated carrier waves, low amplification may 15 be effected without the introduction of harmonics.

We claim:

1. In audion amplifiers of the type in which distortion occurs at low amplification and in which means are provided for controlling over a 20 wide range the amplitude of pulsations in the output circuit resulting from pulsations impressed upon the input circuit of the amplifiers, means for effecting linear amplification throughout the controlling range, which comprises means 25 for impressing the signal energy across the input terminals of a pair of audions, means for adjusting the energizing potentials upon the respective audions to effect non-linear amplification at different rates, and means for delivering 30 the amplified outputs from said audions to a common output circuit in phase opposing relation.

2. In a system for effecting undistorted amplification control of carrier waves over a wide range of intensities, means for impressing the signal 35 in parallel upon two audions, means for impressing the amplified output from said audions upon a common output circuit and in phase opposing relation, and means for adjusting the amplification rates of the individual audions to effect the 40 desired amplification.

3. In audion amplifiers of the type in which modulation distortion occurs at low amplification, and in which means are provided for controlling over a wide range the amplitude of pulsations in the output circuit resulting from pulsations impressed upon the input circuit of the amplifiers, means for effecting low amplification 45 without distortion which comprises means for impressing the signal in parallel upon two audions, means for adjusting amplification control 50 voltages of the respective audions to effect amplification within the square law range of operation but at different rates, and means for combining the amplified outputs from the respective 55 audions in phase opposing relation.

4. The invention as set forth in claim 3, where- 60 in the control grid bias voltage adjusting means is adapted to adjust the grid bias voltages in opposite sense to vary the amplification rates of the respective tubes.

5. The invention as set forth in claim 3, where- 65 in the control grid bias voltage adjusting means is adjusted to adjust the respective voltages in opposite sense to vary the amplification rates of the respective tubes, and in such a way that the sum of the said bias voltages being maintained constant as the separate bias voltages are varied.

6. In a carrier wave amplifier, the combination 70 with an input circuit, an output circuit, and a pair of audions of two sets of impedance elements coupling the respective circuits with said audions, one of said set of impedance elements

being arranged to establish the flow of currents in phase opposing relation between its associated circuit and the respective audions, and the second set of impedance elements being arranged to establish the flow of currents of the same phase 5 between its associated circuit and the respective audions; and means impressing upon said audions energizing potentials of such magnitudes that both audions operate upon curved portions of their respective characteristic curves.

7. In an amplifier stage having an input circuit and an output circuit, means for controlling the amplitude of pulsations in the output circuit resulting from pulsations impressed upon the input circuit thereof over a wide range comprising a 15 pair of audions, circuit elements connecting the input terminals of said audions in parallel across an input circuit, anode circuits individual to the respective audions, an output circuit to which said anode circuits are coupled in phase opposing relationship, and means impressing upon the respective audions energizing voltages of such different and related magnitudes that substantially linear amplification is effected by said stage.

8. The invention as set forth in claim 7, in combination with means for adjusting an energizing voltage on one audion to control the net amplification of said stage.

9. The invention as set forth in claim 7, in combination with means for simultaneously adjusting energizing voltages on the respective audions to vary the amplification ratios thereof in opposite sense.

10. In an amplifier stage having an input circuit and an output circuit, means for controlling the amplitude of pulsations in the output circuit resulting from pulsations impressed upon the input circuit thereof over a wide range comprising a pair of audions, an input circuit connected to said audions to energize the same in parallel, 35 coupling impedances individual to the anode circuits of the respective audions, an output circuit to which said coupling impedances are coupled in opposing relationship, and means impressing upon each of said audions amplification controlling voltages of different magnitude and of such value that both of said audions operate upon curved portions of their respective characteristic curves.

11. The invention as set forth in claim 10, in 50 combination with means for adjusting the control voltage impressed upon one of said audions.

12. The invention as set forth in claim 10, in combination with means for varying in opposite 55 sense, the control voltages impressed upon said audions.

13. The steps in a method of controlling the degree of amplification of signalling energy which comprise, utilizing a portion of the signalling energy to produce a non-linearly amplified 60 related electrical energy output, utilizing another portion of the signalling energy to produce a non-linearly amplified electrical energy output of different intensity than the first named output and combining the two non-linearly amplified outputs 65 in phase opposition so that the effective amplification of the signal energy is determined by the difference in the intensity of each of the produced outputs.
